DOOR CHECK

Philip J. Harrah and Chester P. Harrah,
Bloomfield, Ind.

Application September 9, 1937, Serial No. 163,002

6 Claims. (Cl. 16—51)

This invention relates to improvements in door checks employing toggle levers for securing maximum pressure and also employing a piston reciprocating through a liquid flowing through 5 ports from one side of the piston to the other for regulating the rate of movement of the door by varying the size of the ports.

The object of the invention is to balance the toggle action on the piston and to provide an 10 easy means for varying the size of the ports acting with the lever to control the rate of movement of the door.

A further and important object is to control the opening and closing of the toggle levers and 15 eliminate a fixed and solid attachment of the levers to the door thereby obviating pressure or strain on the door hinges.

Another object is to provide a door check which 20 can be adapted to heavy, medium, or light doors by changing the size of the toggle lever operating springs, and to provide a door check which 25 is operative with four or only two levers, and which can be turned either side up for right or left door fittings, and which can be placed in any desired height on the door.

The object also is to provide a bar or lever 30 which will raise or lower the piston rod in a door check without interference caused by varying position of hinges on different doors.

We accomplish the above and other objects 35 which will hereinafter appear by the mechanism illustrated in the accompanying drawing, in which—

Fig. 1 is a side elevation of parts of a door and 40 door frame member with our invention applied thereto in contracted or closed position of the door;

Fig. 2 is a top plan view of same with a dash 45 line indicating the center position of the door when open and the dotted lines indicating the door and door check when past the center position;

Fig. 3 is a detail on an enlarged scale of the 50 cylinder in vertical section;

Fig. 4 is a detail in front elevation of the 55 bar on which the door check is assembled;

Fig. 5 is a side elevation similar to Fig. 1 of 60 a modified form of my device; and

Fig. 6 is a jamb bracket used in some 65 installations.

Like characters of reference indicate like parts 70 in the several views of the drawing.

In the drawing 6 indicates a door frame member, in this instance a casing, and 7 a door pivotally mounted by hinges 8 in the usual man-

ner. A plate 9 has screw holes therethrough for the passage of screws 10 by which the plate is fastened securely to the casing 6, and formed on the plate 9 is a U-shaped bracket 11 having a hole in the outer end of each leg to receive a hinge pin 12 having a head at its upper end and screwthreaded at its lower end where it receives a nut to prevent the accidental withdrawal of the pin. Hingedly mounted on the pin 12 is a clip 13, here shown as a metal plate bent U-shape with a middle cylinder to surround the pin and each leg extended and formed into a pair of ears, the ears of one leg mating with corresponding ears of the other leg to form new pairs between which the ends of toggle levers 14 and 15 are pivoted by pins 16 and 17 inserted through holes for that purpose formed in the ears. The purpose of the toggle levers will be presently explained.

The U-shaped bracket 11 has holes through each leg near the plate 9, through which a second hinge pin 18 is passed and by which an end of a bar 19, which we designate as a tie-bar, is hinged to the bracket. As here shown this bar 19 is stamped out of sheet steel and for maximum strength and stiffness has its longitudinal edges bent out at right angles into flanges 20 and 21. These flanges at the opposite end of the bar from its hinge, are extended into ears 22 and are perforated to receive a hinge pin 24, similar in all respects to the hinge pin 12, by which a clip 25, in all respects like the clip 13, is hinged to the tie-bar.

The outer end of the tie-bar 19 is formed into a curved flange 26 to stiffen the bar transversely 35 and also to cause that end to slide against the door without marring the door. The tie-bar 19 is preferably further stiffened by the longitudinal corrugations 27.

Pivottally mounted in the clip 25 are the ends 40 of toggle levers 28 and 29 which are duplicates of the levers 14 and 15. All four of the levers 14, 15, 28 and 29 are bent or cranked to slightly S-shape. The lower pairs 15 and 29 have adjacent ends pivottally secured to corresponding ears of a clip 30 which is fixed to the lower end closure of a vertical cylinder 31. Reciprocating within the cylinder is a piston 32 having a rod 33, the outside end of which has a head which is fixed in a clip 34, having ears 35, 36, to which 45 the adjacent ends of levers 14 and 28 are pivottally, or in other words, hingedly attached.

The lever 14 is connected to the lever 15 by a spring 36 and the levers 28 and 29 are connected by a spring 37.

The tie-bar 19 is provided with a longitudinal slot 38 adjacent the end farthest from hinge 18, and a wood screw 39 is passed through the slot into the door as shown in Fig. 2. A fiber washer 5 is preferably placed around the screw between the tie-bar and the door.

Referring now to Fig. 3, the piston rod 33 is hollow. It is externally screw threaded at its lower end and a metal washer 40 having 10 a threaded hole is screwed on the rod 33 as far as it will go. Then a leather 41 is placed against the washer 40 and is followed by a washer 42, not threaded, and after that a threaded nut 43 is screwed on the end of the piston rod to hold the 15 assembly.

Formed through the wall of the hollow piston rod 33 is an oil port 44 and formed through the bottom of the cap 43 is a port 45. As the piston 20 32 is forced down the oil will be forced from below the piston through the ports to above the piston, and conversely when the travel of the piston is reversed.

A rod 46 fills the bore of the rod 33 to and closing the port 44, partially or completely, depending upon the extension of rod 46 into rod 25 33. This extension is regulated at an enlarged and threaded end of rod 46, screwing into a threaded socket in the head end of the rod 33. The rod 46 can be screwed in or out by the aid of 30 a screwdriver. A plug 47 in the lower end of the cylinder affords access for drainage and filling of the cylinder.

A wire cloth strainer 48 is located in the cap 43 to prevent the entrance into the ports of foreign 35 matter that might clog them.

In the modification shown in Fig. 5 the two lower toggle levers are omitted by fastening the lower ends of the two springs to the ears of a bracket 49. The bracket is secured by a ball and 40 socket joint to a hanger depending from the tie-bar 19. The bracket also supports the cylinder.

To pack around the piston rod when it leaves the top of the cylinder, we form a cup 51 through which the piston rod passes. The cup 51 is filled 45 with packing rings which are pressed by a gland 52 screwing into the threaded end of the cap.

In the operation of our device when the door is closed the piston is near the lower end of the cylinder and in opening the door the hinge pins 12 50 and 24 are brought nearer together, spreading the toggle levers 14 and 28 further away from the toggle levers 15 and 29 and carrying the piston rod 33 upward and lowering the cylinder 31; also equally straining the springs 36 and 37 55 which act to check the spreading apart of the levers. The reverse movement of the piston is accomplished by closing of the door. The contraction of the springs forces the hinge pins apart closing the door and also lowers the piston in the oil and the resistance is regulated by the size of the orifice controlled by the position of rod 46, the change in size permitting a variation in closing speeds of the door.

By hinging the levers 28 and 29 to the tie-bar 60 19 instead of to the door, the parts of the device are all assembled ready for use, only requiring that the plate 9 be screwed to the door frame member and the tie-bar secured to the door by inserting screw 39 through the slot 38 into the door. When the pin 18 is in alignment with the pintle of hinges 8 of the door, the slot and 70 its screw 39 are not required.

The jamb bracket, shown in Fig. 6, is used on some installations where there is no available 75 door frame member for other attachment.

By the use of the tie-bar pivoted to the same bracket as the door check, but at separated points, pivoting the other end of the door check to the tie-bar and slidingly contacting that end of the tie-bar against the door, the three resulting pivotal points are made uniform regardless of how the door itself is hinged and the door hinges are relieved from much of the strain. 5

We claim:

1. In a door check for a hinged door, having a frame member and having a movable cylinder, a piston reciprocating therein, a piston rod and a port from one side of the piston to the other, a bracket fastened to the door frame member, a pair of toggle levers pivotally supported from the outer end of the bracket having the other end of one of the levers pivotally attached to the piston rod and the other end of the other lever pivotally attached to the cylinder, a tie-bar hinged at one end to the bracket and attached to the door, a second pair of levers pivotally supported from the end of the tie-bar remote from the hinge of the bar, the other end of one of the last levers pivotally attached to the piston rod and the other end of the other of said last levers pivotally attached to the cylinder and a pair of springs, one on each side of the cylinder, connecting the pair of levers on that side of the cylinder. 15

2. For a hinged door having a frame member, 20 a bracket attached to the frame member, a door check attached to the bracket and a bar attached to the bracket closer to the door and bearing slidingly at its other end against the door. 25

3. For a hinged door having a frame member, 30 a bracket fastened to the frame member, a tie-bar hinged at one end to the bracket and a door check hinged to the bracket and sliding against the door at its other end as the door is swingingly moved, and to the tie-bar. 40

4. For a hinged door having a frame member, a bracket fastened to the frame member, a tie-bar hinged at one end to the bracket, means for securing the bar to the door to allow for longitudinal adjustment of the bar on the door, a cylinder, a piston reciprocating therein having a rod and a by pass from one side to the other of the piston, a pair of levers hinged at adjacent ends to the end of the bracket and at their other ends to the piston rod and lower end of the cylinder respectively, a second pair of levers on the other side of the cylinder from the first pair having adjacent ends hinged to the end of the tie-bar remote from the hinged end of the bar and said levers having their other ends hinged to the piston rod and to the lower end of the cylinder respectively. 50

5. For a hinged door having a frame member, a bracket attached to the frame member, a bar pivotally attached at one end to the bracket and slidingly bearing at its other end against the door and a door check pivoted at one end to the bracket at a point more remote from the base of the bracket than where the bar is pivoted and said door check pivoted at its other end to the bar. 60

6. For a hinged door having a frame member, a bracket attached to the frame member, a door check, a tie-bar pivoted to a fixed support at one end and sliding against the door at the other end as the door is swingingly moved, said door 7 check and tie-bar pivoted at different distances from the frame member.
